UNITED STATES PATENT OFFICE.

LESTER L. GLIDDEN, OF NATICK, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

HEELING-MACHINE.

1,321,202.

Specification of Letters Patent. Patented Nov. 11, 1919.

Application filed March 12, 1917. Serial No. 154,176.

To all whom it may concern:

Be it known that I, LESTER L. GLIDDEN, a citizen of the United States, residing at Natick, in the county of Middlesex and State of Massachusetts, have invented certain Improvements in Heeling-Machines, of which the following description, in connection with the accompanying drawings, is a specification, like reference characters on the drawings indicating like parts in the several figures.

This invention relates to heeling machines and, more particularly, to that type of heeling machine which is adapted to attach heels to shoes while the shoes are still on the wooden last upon which they are made.

In heeling shoes upon the wooden last, it is well known to those skilled in the art that there is danger of crushing or damaging the last if too great a pressure is applied to the work in the heel attaching operation. It is the general object of the present invention to provide a heeling machine equipped with mechanism for preliminarily measuring and applying the final pressure to the work without the liability of damaging the last while, at the same time, the attaching operation is uniformly and accurately performed.

In pursuance of the general object above stated, and other objects, one important feature of the invention resides in the provision in a heeling machine of measuring mechanism and positive final pressure mechanism with connections between the two for keeping the operation of one of said mechanisms under the control of the other. The final pressure mechanism is preferably separate from, and under the control of, the measuring mechanism, the construction and arrangement being such that the final pressure mechanism is maintained in predetermined operative relation to the work support, regardless of the variable amount of movement imparted to the latter by the measuring mechanism when operating upon work of different thicknesses. In a convenient construction, the measuring mechanism is positively connected to a beam carrying the work support, and the final pressure mechanism is so connected to the beam, or to the measuring mechanism, that it remains in engagement with the beam, or at a predetermined distance therefrom, throughout the

movement of the latter during the measuring operation.

Another feature of the invention resides in improved means for locking the work under pressure while the nails are being driven. In the specific embodiment of the invention which has been selected for the purpose of illustration, the work support is connected to one end of a toggle, the other end of which is stationary, and the toggle is straightened more or less during the measuring and the application of the final pressure. A separate locking device connected to the center of the toggle automatically operates to prevent breaking of the toggle under the pressure applied to the work.

It has been many times observed in the operation of machines of this general type that while the nails are being driven into the heel, the upward pressure due to the nail driving is sufficient to raise the heel slightly from the nailing die, even though the work support may be solidly locked against movement. Under these conditions there is danger that the nails will be crippled and the work damaged. In this connection, another important feature of the invention resides in the provision of improved means for progressively and gradually increasing the pressure upon the work during the progress of the nail driving operation. I have found that this effectually overcomes the difficulty mentioned and greatly reduces the liability of crippling the heel nails.

Other features and advantages of the invention will be apparent from the following detailed description of a specific embodiment of the same, when read in connection with the accompanying drawings, in which,

Figure 1 is a view in side elevation of a heeling machine embodying the invention;

Fig. 2 is a perspective view of the rear portion of the machine;

Fig. 3 is a longitudinal section of the pressure locking and releasing mechanism;

Fig. 4 is an exploded view of the pressure locking mechanism;

Fig. 5 is a perspective view illustrating the details of the unlocking mechanism; and

Fig. 6 is a fragmentary view of the treadle mechanism for controlling the operation of the machine.

Referring to the drawings, a conventional

heeling machine frame or base is represented at 10. A stationary nailing die 12 has the usual holes in which the nail drivers 14 travel. The drivers are carried upon a reciprocating spindle 16 which is actuated by a toggle 18 and connecting rod 20, connected to the crank pin 22 of the crank shaft 24. 26 represents the stop arm of a one-revolution Horton clutch arranged to control the 10 operation of the crank shaft. The arm 26 is normally held in engagement with the clutch stop member, to permit the crank shaft to remain stationary, by a pull spring 28.

15 A jack or work support 30 depends from the forward end of the top lever 32, which is pivotally mounted in the frame 10 at 34. The upper end of the back rod 36 is pivotally connected to the rear end of the top lever 32 at 38.

20 Secured to the lower end of the rod 36 is a piston 38 suitably guided for vertical reciprocation in a cylindrical bore formed in a bracket 40 secured to the rear of the frame 10.

25 Strong pull springs 42 are attached at 44 to the lower end of the piston 38. The upper ends of the springs are engaged by hooks 46, which are adjustable to vary the 30 tension of the springs by means of bolts 48 threaded into a stationary bracket 50 secured to the machine frame. The springs 42 are always under tension and tend to elevate the rod 36 and consequently to lower 35 the jack 30; bringing the shoe and heel together under some pressure. This is technically known as "measuring" the work.

40 One link 52 of a toggle is also pivotally connected to the lower end of the back rod 44, and the other link 54 of the toggle is pivoted at a stationary point 56. The center of the toggle is connected by a link 58 to a pressure locking screw 60. The screw 60 is guided for reciprocating movement 45 through a stationary bracket 62 and a nut 64. The outer surface of the nut is conically formed and the nut is located in a correspondingly conically formed recess in the casting 66 secured to the frame 10. The screw 60 is slotted at 68, see Fig. 4, to permit the passage of a transverse bar 70, which engages a ball thrust bearing 72 resting upon the upper end of the nut. Another ball thrust bearing 74 is provided 55 at the opposite end of the nut 64. Tension springs 76, acting upon the ends of the bar 70, tend to draw the nut downwardly and seat it frictionally in the conical recess in the casting 66. A cap plate 78 covers the 60 recess.

65 When the measuring springs 42 are permitted to operate to move the back rod 36, the toggle 52, 54 will be straightened more or less according to the amount of movement of the rod. This straightening of the

toggle is accompanied by a longitudinal movement of the screw 60 through the nut 64, free rotation of which is permitted by reason of the nut being drawn upwardly against the ball bearing 72. As soon, however, as the longitudinal movement of the screw ceases, the springs 76 draw the nut downwardly and seat it frictionally in its conical bearing, where it acts as a locking device to prevent movement of the screw 75 and, consequently, to prevent any yielding or reverse movement of the back rod 36, which cannot occur without breaking the toggle 52, 54.

80 In order to maintain the toggle in broken condition and the jack separated from the nailing die to permit removal and insertion of the work, mechanism is provided, which will now be described. Connected to the center of the toggle 52, 54 is one end 85 of a link 80, the other end of which is pivotally connected to the upper end of a rocking lever 82, mounted to oscillate about a stationary pivot 84. A latch bar 86 is connected at an intermediate point upon the 90 lever 82. The forward end of the latch bar is formed with a shoulder 88, as shown in Fig. 6, which is normally held in engagement with a stationary stop 90 by a spring 92 which is under tension, tending to elevate the bar. When the parts just described are in the position shown in the drawings, the toggle 52, 54 is maintained in its broken position with the measuring springs 42 under tension.

95 A treadle 94 is pivoted at 96 in the frame 10. A latch bar tripping finger 98 is mounted upon the treadle and arranged to overlie the forwardly projecting end 100 of the bar 86. When the treadle is depressed the forward end of the bar is depressed, against the tension of the spring 92, until the shoulder 88 passes below the stop 90. The measuring springs 42 may then operate to measure 110 the work, this operation being accompanied by a straightening of the toggle 52, 54 and a forward movement of the bar 86.

115 A link 102 is pivoted to the rear end of the treadle and is provided with a slot 104 which forms a lost motion connection with a pin 106 mounted in the clutch stop arm 26. Thus, after the release of the bar 86 and the consequent operation of the measuring mechanism, further depression of the treadle will cause the machine to be started.

120 Upon starting the machine, the first thing to be done is to apply the final pressure to the work preparatory to driving the nails. For this purpose I have provided mechanism under the control of the measuring mechanism. A pair of pressure cams 108 is mounted upon the crank shaft 24. Resting upon these cams is a pair of cam rolls 110 mounted in the lower forked end of a slide 112 which is guided for vertical recip-

location in a guide 114 secured to the machine frame. The lower ends of the fork are provided with slots 116 embracing the crank shaft 24 and serving to guide the 5 lower end of the slide. To the upper end of the slide 112 is pivoted a swinging arm 118. A pressure head 120 is threaded into the upper end of the arm 118 and arranged for engagement with the under face of a block 10 10 122 mounted upon the rear end of the top lever 32. The arm 118 is connected by a link 124 to one arm of a bell crank lever 126 pivoted to the frame 10 at 128. The other arm of the bell crank lever is pivoted 15 to a connecting member 130 provided with a slot 132 which embraces the pivot 38 at the rear end of the lever 32. A spring pressed plug 134 in the upper end of the connecting member 130 bears upon the pivot 20 38, tending to hold it in the bottom of the slot 132.

The curvature of the lower face of the block 122 is such that when the rear end of the top lever 32 is moved upwardly in the 25 measuring operation and, consequently, by reason of the connections 130, 126, 124, the arm 118 is swung rearwardly, the pressure head 120 moves in a path parallel to the face of the block; that is to say, the pressure head is always at the same distance from the block, regardless of the upward or downward movement of the lever. This distance may be varied, and, consequently, the amount of final pressure to be applied to 30 the work may be regulated, by adjusting the pressure head into or out of the arm 118. The adjustment is maintained by any suitable means, such as a set screw 136.

For the purpose of unlocking and releasing the pressure after the nails have been driven, a cam 138 is mounted upon the crank shaft 24 and the rock shaft 140, which is journaled in the bracket 40 is provided with an arm 142 having at its extremity a cam roll 144 held in engagement with the cam 138 with a spring 146. Another arm 148, secured to the rock shaft, is connected by an adjustable link, embodying a turn buckle 150, to an arm 152 upon a shaft 154. An arm 156 secured to the shaft 154 is connected by a link 158 to an unlocking lever 160 pivoted at 162 in the casting 66. The lower end of the lever 160 is forked and arranged to engage the cover plate of the ball thrust bearing 74. When the cam roll 144 is in the depressed portion of the cam 138, the forked end of the lever 160 is retracted sufficiently to permit the locking cone 64 to settle into its bearing and be frictionally locked against rotation, but at the proper point in the revolution of the crank shaft, after the nails have been driven, a rise on the cam 138 causes the unlocking lever 160 to be moved to lift the conical 55 60 65 70 75 80 85 90 95 100 105 110 115 120 125 130 nut out of its seat, whereupon it is per-

mitted to rotate freely while the screw 60 is pushed downwardly through it and the back rod 36 retracted. To effect this longitudinal movement of the screw and retraction of the back rod, a roll 164 is mounted 70 upon the pivot connecting the lever 82 and the link 80, and is arranged to be engaged by a hardened plate 166 upon the rear end of the connecting rod 20 as the connecting rod approaches the limit of its return stroke 75 toward stopping position. A stop screw 168, threaded into the bracket 62, controls the limit of retraction of the lower end of the lever 160. When the connecting rod 20 in its return movement, through the roll 164 80 and link 80, has broken the toggle 52, 54 and restored it to initial position, the latch bar 86 is raised by the spring 92 until the shoulder 88 engages the stop 90, holding the parts against the tension of the measuring springs.

The operation of the machine is as follows: The machine being at a standstill with the parts in their initial positions, as shown in the drawings, a shoe is jacked and a heel and top lift inserted in the holder. With the work in position, the treadle is depressed sufficiently to unlatch the bar 86, whereupon the measuring springs 42 operate to elevate the back rod 36 and lower the jack to seat the shoe firmly upon the heel. This operation is accompanied by a straightening of the toggle 52, 54, and a movement of the screw 60 through its nut, which is drawn up against the ball thrust bearing 72 and consequently permitted to rotate freely. As soon as the movement of the screw ceases, the springs 76 cause the nut 64 to settle down into its conical bearing, where it is frictionally held against rotation, locking the work under the pressure of the measuring springs. Further depression of the treadle causes the clutch stop arm 26 to be thrown forwardly and the crank shaft of the machine to be turned through a revolution. A rise on the cam 108 immediately causes the slide 112 and the arm 118 to be raised through a fixed distance. During this upward movement the pressure head 120 engages the block 122 and applies the final pressure to the work. The pressure head has been maintained at a predetermined distance from the block 122 during the measuring operation by the connections previously described, and the amount of the final pressure is determined by the distance through which the pressure head travels upwardly before it encounters the block. The holes in the nailing die 12 are sufficiently deep so that the points of the nails do not enter the heel until after the final pressure has been applied. The upward movement of the back rod 36, incident upon the application of the final pressure, is accompanied by further movement of the screw 60 through its 130

nut, and the nut is again drawn down into its seat, locking the work under the final pressure. Thereupon, the further rotation of the crank shaft causes the nails to be driven through the heel into the shoe. The cam 108 is formed with a small and gradual rise from the point where the nail driving operation begins to the point where it is finished, so that a progressively increasing pressure is being applied to the work as the driving of the nails progresses. It has been found that this application of progressively increasing pressure during the nail driving operation prevents the work from being separated from the nailing die with a resultant possibility of crippling the nails.

After the nails have been driven, and while the drivers are being retracted, the rolls 110 drop off the high portions of the cams 108, releasing the work from positive pressure. The cam 138 then operates, through the train of connections shown in Fig. 5, to unlock the conical nut 64 and raise it from its seat sufficiently to permit it to rotate freely. The roll 164 is then engaged by the plate 166 on the end of the connecting rod and the operating mechanism is retracted to its initial position, whereupon the roll 144 drops off the high portion of the cam 138, the latch bar 86 is engaged with its stop, and the machine is stopped, ready for a repetition of the operation. If the work is blind nailed, the treadle is again immediately depressed and the top lift spanked upon the heel, the machine operating in precisely the same manner as when nailing the heel, except that no nails are driven.

Having described the invention, what is claimed as new and desired to be secured by Letters Patent of the United States is:—

1. In a heeling machine, the combination of a stationary work pressing member, an opposed pressing member movable toward and from said stationary member, measuring mechanism for preliminarily moving the movable member into pressing engagement with the work, and final pressure mechanism including a power-operated member having a fixed stroke, and automatically variable connections between the power-operated member and the movable work engaging member.

2. In a heeling machine, the combination of a stationary work-engaging member, an opposed work engaging member movable toward and from the stationary member, measuring means for preliminarily moving the movable member into pressing engagement with the work, and positive final pressure mechanism including a power-operated plunger, variable connections between the plunger and the movable work-engaging member, and means controlled by the movement of said work engaging member for pre-

serving a substantially constant actuating relation between the plunger and the member.

3. In a heeling machine, the combination of a stationary nailing die, an opposed jack movable toward and from the die, measuring means operable preliminarily to move the jack into pressing engagement with the work, and final pressure mechanism including a power operated plunger, variable connections between the plunger and the jack, and jack operated means for controlling said connections to preserve a substantially constant relation between the plunger and the jack.

4. In a heeling machine, the combination of a stationary nailing die, a movable jack, a power-operated final pressure member, means for effecting measuring movement of the jack independently of the final pressure member, and means connected to and operated by movement of the jack for preserving a substantially constant operating relation between said member and the jack.

5. In a heeling machine, the combination of means for suddenly subjecting the work to final pressure, means for driving nails, and means for gradually increasing the final pressure upon the work after the beginning of the nail driving operation.

6. In a heeling machine, the combination of means for suddenly subjecting the work to final pressure, means for driving nails, and means for more slowly increasing the final pressure upon the work during the entire nail driving operation.

7. In a heeling machine, the combination of means for suddenly subjecting the work to final pressure, means for driving nails, and means for progressively increasing the final pressure upon the work throughout the progress of the nail driving operation.

8. In a heeling machine, the combination of means for suddenly subjecting the work to final pressure, means for driving nails, and means for progressively and gradually increasing the final pressure upon the work during the progress of the nail driving operation.

9. In a heeling machine, the combination of a work support, means for moving the work support to apply pressure to the work, and a pressure locking device comprising a toggle, one end of which is connected to the work support and the other end of which is held against movement while the work is under pressure, the construction and arrangement being such that the toggle is progressively straightened as the work support is moved to apply pressure to the work, and means for preventing breaking of the toggle, whereby the work is locked under pressure.

10. In a heeling machine, the combination of a work support, means for moving the work support to apply pressure to the work,

and a separate pressure locking device comprising a toggle constructed and arranged to be progressively straightened by the pressure applying movement of the work support, and means for preventing breaking of the toggle, to hold the work locked under pressure.

11. In pressure mechanism for heeling machines, the combination of a work engaging member, supporting means for said member, power mechanism for moving said supporting means and member to apply pressure to the work, lost motion connections between the power mechanism and said member, means connected to said member for effecting a preliminary work measuring operation, and means under the control of said measuring means for preserving a uniform amount of lost motion in said connections throughout the operation of the measuring means.

12. In pressure mechanism for heeling machines, the combination of a work engaging member, power mechanism for moving said member positively to apply pressure to the work, lost motion connections between said power mechanism and said work engaging member, means for preliminarily adjusting the amount of lost motion in said connections to vary the pressure to be applied, means for preliminarily moving said

member into pressing engagement with the work to measure the work, and connections between the measuring means and the lost motion mechanism whereby the operation of 35 the latter is under the control of the former.

13. In a heeling machine, the combination of a work engaging member, a beam supporting said member, power operated means including a swinging arm and a coöperating curved face on the beam for moving said member to apply pressure to the work, independent means for preliminarily moving the beam to measure the work, and connecting means between the beam and the arm to effect 40 swinging movement of the latter during 45 the preliminary movement of the beam.

14. In a heeling machine, the combination of a work engaging member, a beam supporting said member, power mechanism for 50 moving said beam and member to apply pressure to the work, connections between said power mechanism and said beam, including a curved face upon the beam and a member mounted to swing in a path parallel to 55 said curved face, measuring mechanism, and connections between the measuring mechanism and the swinging member to effect swinging movement of the latter.

In testimony whereof I have signed my 60 name to this specification.

LESTER L. GLIDDEN.
